ROLL PAPER DISPENSER

Frederick Dale Smith, Ferguson, Mo.

Application December 30, 1957, Serial No. 49,057

Term of patent 14 years

(Cl. D4—3)

FIG. 1.

FIG. 2.

Figure 1 is a perspective view of a roll paper dispenser, showing my new design.

Figure 2 is a side elevational view of the lower portion thereof on a smaller scale.

I claim:

The ornamental design for a roll paper dispenser, substantially as shown.
